(72) Inventor: Kiak Sing Ang, Singapore (SG)

Primary Examiner — Khawaja Anwar

() Term: 15 Years

(57) CLAIM

(21) Appl. No.: 35/511,288

The ornamental design for document folder, as shown and described.

(22) Filed: Jan. 4, 2021

DESCRIPTION

(80) Hague Agreement Data

Int. Filing Date: Jan. 4, 2021

Int. Reg. No.: DM/212396

Int. Reg. Date: Jan. 4, 2021

Int. Reg. Pub. Date: Feb. 5, 2021

The patent or application file contains at least one drawing executed in color. Copies of this patent or patent application publication with color drawing(s) will be provided by the Office upon request and payment of the necessary fee.

FIG. 1.1 is a perspective view of a document folder, showing our new design;

FIG. 1.2 is another perspective view thereof;

FIG. 1.3 is another perspective view thereof;

FIG. 1.4 is a top plan view thereof;

FIG. 1.5 is a bottom plan view thereof;

FIG. 1.6 is another perspective view thereof;

FIG. 1.7 is another perspective view shown thereof, in an open configuration;

FIG. 1.8 is bottom plan view thereof;

FIG. 1.9 is another perspective view shown thereof, in an open configuration; and

FIG. 1.10 is another perspective view shown thereof, in an open configuration.
